(57) **CLAIM**

The ornamental design for a suspension bracket for wallform, as shown and described.

DESCRIPTION

FIG. 1 is a front, top, right perspective view of a suspension bracket for wallform, showing our new design.

FIG. 2 is a back, bottom, left perspective view thereof.

FIG. 3 is a front elevation view thereof.

FIG. 4 is a right-side elevation view thereof; the left-side elevation being a mirror image thereof.

FIG. 5 is a back elevation view thereof.

FIG. 6 is a top plan view thereof; and,

FIG. 7 is a bottom plan view thereof.
